WIRE-STITCHING MACHINE

George H. Harred, East Greenwich, R. I., assignor
to Boston Wire Stitcher Company, Portland,
Maine, a corporation of Maine

Application April 27, 1943, Serial No. 484,688

15 Claims. (Cl. 1--11)

The present invention relates to stapling or wire-stitching machines for stitching the seams of corrugated paper and fiber-board boxes or cartons, and more particularly to improvements in such machines to adapt the box-blanks to be stitched closely adjacent their leading edges as they are advanced through the machine.

Wire-stitching machines have been used extensively for stitching the "manufacturer's seams," so-called, of slotted boxes or cartons having closure flaps at their ends which are adapted to be folded inwardly to form the top and bottom of the finished article. In such machines the leading edges of the closure flaps engage and actuate a gauge to initiate operation of the wire-stitching means. Considering that the box-blanks are inserted at the front of the machine and fed toward the rear thereof the abutment of the gauge in such machines is positioned beyond or rearwardly of the stitch-line of the wire-stitching means a distance equal to the length of the closure flaps. While the abutment of the gauge is usually adjustable to adapt the machine to stitch boxes with closure flaps of different lengths, the construction of the gauge and other elements of the machine is such as to limit the setting of the gauge close to the stitch-line. That is to say, at the forward limit of adjustment of the gauge the abutment is still an appreciable distance to the rear of the stitch-line of the wire-stitching means. In such prior art machines the feed-rolls for advancing the work between stitches are positioned at the rear of the wire-stitching means and are adapted to engage the closure flaps to initiate the feeding of the blank. However, with certain types of work such as "tubular boxes" having only four sides and open ends, it is desirable to stitch the manufacturer's seam closely adjacent the leading edge of the blank as it advances to engage the gauge.

One of the objects of the present invention is to provide a machine of the type indicated which is adapted to stitch the manufacturer's seam of a tubular box-blank or similar work closely adjacent the leading edge thereof as the blank advances.

Another object is to provide a machine of the type indicated with cooperating feed-rolls positioned forwardly of the stitch-line of the wire-stitching means to advance the work between stitches when stitched closely adjacent the leading edge of the blank.

Another object is to provide a machine of the type indicated with auxiliary feed-rolls adapted to be driven from the main feed-rolls.

Another object is to provide a machine of the type indicated with a gauge adapted to be adjusted to a position closely adjacent the stitch-line of the wire-stitching means.

Another object is to provide auxiliary feed-rolls and a gauge for use as attachments to standard machines to adapt them to stitch work closely adjacent the leading edge of the blank.

Still another object is to provide such improvements in a machine of the type indicated as are of simple and compact construction, adapted for economical manufacture and efficient in operation.

10 Further objects of the improvement are set forth in the following specification which describes a preferred construction of the invention, by way of example, as illustrated by the accompanying drawings. In the drawings:

15 Fig. 1 is an end elevational view of a wire-stitching machine incorporating the novel features of the present invention and showing the relationship of the auxiliary feed-rolls and the abutment of the gauge to adapt the machine for stitching the work closely adjacent the leading edge of the blank.

20 Fig. 2 is a front elevational view of the wire-stitching head showing a tubular box-blank gripped between the auxiliary feed-rolls while being advanced during a stitching operation;

25 Fig. 3 is an enlarged detailed view of the work-operated gauge showing the relationship of the parts prior to a stitching operation;

30 Fig. 4 is a view similar to Fig. 3 showing the pivoted gauge-abutment rocked by the work to actuate the sliding plate of the gauge and initiate the operation of the wire-stitching means to apply the first stitch;

35 Fig. 5 is a view similar to Fig. 3 showing the abutment rocked to permit the work to pass between it and the trip-member of the gauge;

40 Fig. 6 is a detailed plan view of the gauge with the parts shown in the relative positions illustrated in Fig. 3;

45 Fig. 7 is an enlarged front elevational view of the work-operated gauge showing the trip-member as in position to adapt it to be actuated by the rocking movement of the abutment;

50 Fig. 8 is a view similar to Fig. 7 showing the trip-member as actuated by the wire-stitching means to release the gauge from engagement with the rockable abutment; and

55 Fig. 9 is a perspective view of a tubular box showing the manufacturer's seam stitched closely adjacent its ends.

Referring to the drawings, the present invention is shown as applied to a wire-stitching machine of the type illustrated and described in my prior patent, No. 2,305,418, issued December 15, 1942. It is to be understood, however, that the improvements of the present invention can be applied to the type of wire-stitching machine illustrated and described in my prior patent, No. 2,266,550, issued December 16, 1941, and also to

60 other types. Suffice it to state herein, that the

present machine comprises a wire-stitching head 2 mounted on the end of a horizontal arm 3 for operation by a suitable drive-shaft 4 extending longitudinally through the arm, see Figs. 1 and 2. The wire-stitching head 2 may be of any suitable construction and, as herein illustrated, is of the type shown and described in United States Letters Patent No. 1,760,031 issued May 27, 1930, to H. G. Allen. In the operation of this type of machine, during the first half revolution of the drive-shaft 4 a length of wire is cut from the supply, formed into a U-shaped staple, driven into the work and clinched on the under side thereof; and during the second half revolution of the drive-shaft 4 the parts of the stitching mechanism are returned to initial position and another length of wire is fed into the head. The drive-shaft 4 may be connected to a suitable prime-mover by an electro-magnetically-operated clutch, not herein shown, in the manner illustrated and described in my prior patent, No. 2,305,418, referred to above. Below the wire-stitching head 2 is a work-supporting table 5 which may be mounted in any suitable manner on the machine-frame. Depending from the stitching head 2 is a combined flap-guide and clinching anvil 6 of usual construction having clinching grooves 7 adjacent its rearward end.

The work in the form of a folded box-blank W is fed either continuously or intermittently in timed relation to the operation of the wire-stitching head 2 by means of cooperating feed-rolls 8 and 9 positioned rearwardly of the stitch-line of the wire-stitching head 2, see Fig. 1. The upper feed-rolls 8 are mounted on a shaft 10 journaled in suitable bearings 11 depending from the head 2 and arm 3. The lower feed-rolls 9 are mounted on a shaft 12 journaled in yieldable bearings 13 at the end of arms 14, see Fig. 1. The opposite ends of the arms 14 are mounted fast on a rock-shaft 15 which extends throughout the length of the machine.

The operation of the wire-stitching head 2 is controlled by a work-operated gauge 18 shown in detail in Figs. 3 to 6. The gauge 18 comprises an upper stationary horizontal plate 19 supported from an arm 20 depending from the frame of the wire-stitching head 2, see Figs. 1 and 3. Slidably mounted on the under side of the stationary plate 19 is a plate 21 having studs 22 projecting through elongated slots 23 in the stationary plate with washers 24 overlying the top face of the latter under the heads of the studs. Fastened to the fixed plate 19 is a switch-block 25 mounting two separate switches having push-buttons 26 and 27, see Fig. 6. The switches may be of any suitable type for closing an electrical circuit when their push-button 26 or 27 is depressed, the push-buttons being normally moved to the open position illustrated in Fig. 6. The sliding plate 21 of the gauge 18 normally is maintained in its forward position, shown in Fig. 6, by means of a spring 28 connected between a pin on the arm 20 which supports the gauge and a pin on a post 30 surmounting the sliding plate.

The operator for the switches comprises the post 30 which is fixedly mounted on the sliding plate 21 and projects upwardly through an elongate slot 31 in the fixed plate 19. The post 30 carries adjustable abutments 32 and 33 engageable with the push-buttons 26 and 27 of the switches and, as herein illustrated, the abutments are in the form of set-screws screwed into the post 30. As shown in Fig. 6, the abutment 32 is adapted to engage and operate the push-button

26 of one switch prior to the engagement of the abutment 33 with the push-button 27 of the other switch.

Mounted in arms 34 and 35 projecting laterally from the opposite ends of the slidable plate 21 is a rock-shaft 36, see Fig. 6. An arm 37 fast on the forward end of the rock-shaft 36 is positioned adjacent a reciprocable member 38 of the stitching head 2 and is adapted to be engaged by a finger 39 thereon during the application of a stitch S to the work. At the opposite end of the rock-shaft 36 is an arm 40 which is adapted to engage with an adjustable abutment 41 offset from the side of the arm 35 to limit the rocking movement of the rock-shaft. As thus far described the construction is substantially identical with that illustrated and described in my prior patent, No. 2,305,418, referred to above.

The sliding plate 21 of the gauge is adapted to be actuated by the work W in a manner later to be described in detail whereby to cause the abutments 32 and 33 to operate the push-buttons 26 and 27 of the switches in succession. Closing of the switch by operation of the button 26 will actuate suitable mechanism to cause the shaft 10 mounting the upper feed-rolls to be disconnected from continuously-operated driving means and to connect the shaft to an intermittently-operating driving means in the manner illustrated and described in detail in my prior patent last referred to. Closing of the second switch by the button 27 will cause the drive-shaft 4 for the wire-stitching head 2 to be driven from a suitable prime-mover to initiate a wire-stitching operation. During a stitching operation the wire-stitching head 2 will apply a staple S to the work while the feed-rolls 8 and 9 remain idle and the feed-rolls then will be rotated to advance the work W while the reciprocating parts of the wire-stitching head are being returned to initial position.

In accordance with the present invention a pair of cooperating auxiliary feed-rolls 44 and 45 and a novel form of work-operated gauge-mechanism are provided to adapt the machine to stitch the work W closely adjacent its leading edge as it is advanced to the stitching means. While the machine is adapted to stitch various kinds of work W the present improvements are provided particularly to adapt the machine to stitch tubular boxes of the type illustrated in Fig. 9. Such boxes are in the form of a rectangular sleeve for enclosing an oblong article when wrapped with a suitable covering. The tubular box-blank W is in the form of a rectangular sheet of fiber-board or the like which is scored longitudinally to provide adjacent panels with a marginal strip at the side of one end panel adapted to overlie the side of the opposite end panel to provide an overlap for the seam. The tubular box-blank W is stitched with a row of staples S to provide a manufacturer's seam throughout the length of the box and the stitches extend closely adjacent the ends thereof.

As illustrated in the present drawings, the auxiliary feed-rolls 44 and 45 may be applied as an attachment to the machine to adapt it to feed folded blanks for forming tubular boxes of the type illustrated in Fig. 9. The upper auxiliary feed-roll 44 is mounted fast on the end of a shaft 49 journaled in a bracket 47 attached to a flange 48 on the arm 3 which supports the head 2, see Fig. 2. Mounted fast on the opposite projecting end of the shaft 49 is a gear 50 for driving the roll. The upper auxiliary feed-roll 44 is driven from the previously described upper

feed-roll 8 by means of an idler gear 51 which intermeshes with a gear 52 on the shaft 10 and the gear 50 on the shaft 49, see Fig. 1.

The lower auxiliary feed-roll 45 is journaled on a stud 53 carried at the outer end of an arm 54 pivotally mounted on the shaft 15. Mounted fast on the shaft 15 at the side of the arm 54 is a crank-arm 55 having a laterally-extending finger 56 at its end which underlies the arm 54. An adjustable abutment in the form of a set-screw 57 extends through the finger 56 on the crank-arm 55 to engage and rock the arm 54 mounting the lower auxiliary feed-roll 45. A similar adjustable abutment 58 is mounted in an extension or tail-piece 59 projecting from the hub of the arm 54 to adapt it to engage against the bottom of the table 5 to limit the rocking motion of the arm and movement of the lower auxiliary feed-roll 45 away from the upper auxiliary feed-roll 44. Counterclockwise rocking motion of the shaft 15 to move the lower feed-roll 9 toward the upper feed-roll 8 will cause the abutment 57 on the crank-arm 55 to engage the arm 54 and rock it upwardly to raise the lower auxiliary feed-roll 45 toward the upper auxiliary feed-roll 44. The cooperating pair of feed-rolls 44 and 45 thus is adapted to grip the work forwardly of the stitch-line of the wire-stitching head 2 to advance it as it is stitched close to its leading edge. While one pair of auxiliary feed-rolls 44 and 45 only is shown in the drawings, it is to be understood that another pair of auxiliary feed-rolls may be provided at the opposite side of the seam to be stitched if desired.

The work-operated abutment 46 of the gauge-mechanism comprises a plate projecting upwardly from the table 5 and having a central clearance recess or opening 62 in its upper edge and depending hinge-ears at its opposite ends. The abutment 46 is pivotally mounted on the ends of a rod 63 held in spaced bearing-blocks 64 and 65 at the forward end of a longitudinally-adjustable plate 66 supported on the table 5. The bearing-blocks 64 and 65 are of identical construction riveted or otherwise attached to the plate 66, see Fig. 6. Each of the bearing-blocks 64 and 65 has a horizontal upper face and a forwardly and downwardly-inclined face 68, see Fig. 3. A helical spring 69 is provided on the rod 63 with one of its ends bearing against the supporting plate 66 and its opposite end bearing against the rearward side of the abutment 46, thereby tending to rock the latter in clockwise direction to the position shown in Fig. 3, the rocking movement of the abutment being limited by the engagement of its bottom edge with the top of the bearing-blocks 64 and 65. The abutment 46, however, is adapted for rocking movement in counterclockwise direction from the position shown in Fig. 3 to that shown in Fig. 5 against the action of the spring 69.

To adapt the plate 66 for adjustment on the table 5 it is provided at its rearward end with longitudinally-extending slots 70 having recesses 71 surrounding the slots. Bolts 72 extend through the slots 70 in the plate 66 and through holes in the table 5, the square heads 73 of the bolts being positioned in the recesses 71. Nuts 74 are screwed onto the shanks of the bolts tightly to clamp the plate 66 to the table 5. To adjust the position of the abutment 46 in relation to the stitching means the nuts 74 are loosened on the bolts 72 and the plate 66 slid longitudinally on the table. Due to the construction of the supporting plate 66 the work-operated abutment 46

may be adjusted to the end of the clinching anvil 6 and closely adjacent the stitch-line of the wire-stitching head 2, see Fig. 3. When once adjusted the nuts 74 are tightened on the bolts 72 to fixedly clamp the plate 66 to the table 5.

Engaging the rearward side of the work-operated abutment 46 is an adjustable extension 78 of a trip-member 79 mounted on the sliding plate 21 of the gauge 18. As illustrated in Figs. 3, 6 and 7, the trip-member 79 is in the form of a plate having pivots 80 adjacent one end which project laterally from its side. The pivots 80 are journaled in depending bearing-blocks 81 attached to the sliding plate 21 of the gauge 18 by means of screws 83, see Fig. 6. The adjustable extension 78 is in the form of an angle-iron having an upper flange 84 overlying the top of the trip-member 79 and a depending flange 85 overhanging its end, the forward end of the depending flange being inclined to provide a cam-face 86 as illustrated in Fig. 3. The upper flange 84 of the extension 78 has a longitudinally-extending slot 87 through which screws 88 extend to clamp it to the trip-member 79. By loosening the screws 88 the extension 78 may be adjusted longitudinally to engage its forward end with the rearward face of the work-operated abutment 46 in any adjusted position of the latter. A compression-spring 89 is provided between the sliding plate 21 of the gauge and the trip-member 79 for normally holding the trip-member and its extension 78 in depressed position as shown in Fig. 7. The spring 89, however, is adapted to yield to permit the trip-member to be rocked to the position illustrated in Fig. 8.

Overlying the trip-member 79 at the opposite side of the pivots 80 from the extension 78 is an actuating arm 90 rigidly affixed to the rock-shaft 36. The arm 90 carries an adjustable abutment in the form of a set-screw 91 at its end for engaging the trip-member 79 during the rocking movement of the rock-shaft 36 to rock the extension 78 out of engagement with the vertical abutment 46 whereof to permit the latter to be rocked to the position shown in Fig. 5. A preferred form of the invention having been described in detail, the mode of operation of the complete machine is explained as follows.

To adapt the machine for stitching the manufacturer's seams of tubular box-blanks W, or similar work, close to the leading edges thereof the plate 66 may be adjusted along the top of the table 5 until the abutment 46 at its forward end is positioned closely adjacent the rearward end of the clinching anvil 6 shown in section in Fig. 3. The nuts 74 then may be tightened on the bolts 72 to clamp the plate 66 in its adjusted position. The extension-element 78 of the gauge also may be adjusted by loosening the screws 88, see Fig. 6, and sliding it relative to the trip-member 79 until its forward end engages the rearward face of the abutment 46, the screws then being tightened to fixedly connect the extension in adjusted position on the trip-member.

To initiate a stitching operation a tubular box-blank W may be folded and inserted into the flap-guide 6 to position the flap on one of its side panels to overlie the side of the opposite side panel of the blank in the manner shown in Fig. 2. As the folded carton-blank W is advanced manually it will be engaged lightly between the auxiliary feed-rolls 44 and 45. The upper auxiliary feed-roll 44, being continuously driven at a high rate of speed from the shaft 10 through the intermeshing gears 52, 51 and 50, will cause the

box-blank W to be advanced automatically until its leading edge engages the abutment 46 and rocks the latter from the position shown in Fig. 3 to that shown in Fig. 4. The rearward movement of the abutment 46 as it rocks on its pivot 63 will be transmitted to the extension 78 of the trip-member 79 to slide the plate 21 of the gauge 18 on which it is mounted, see Figs. 3 and 4. Rearward movement of the sliding plate 21 and post 30 mounted thereon will cause the abutments 32 and 33 to operate the push-buttons 26 and 27 of the two switches in succession.

Upon operation of the push-button 26 of one switch the shaft 10 will be disconnected from its continuously-operating driving means and connected to intermittently-operated driving means by suitable mechanism such as illustrated and described in my Patent No. 2,305,418 referred to above. Upon operation of the push-button of the second switch the main drive-shaft 4 will be clutched to its prime-mover to initiate operation of the stitching head 2 to apply a predetermined number of staples S to the work W.

Due to the position of the carton-blank W at the beginning of a wire-stitching operation, as controlled by the abutment 46, the first staple S will be driven into the work closely adjacent its leading edge, see Figs. 4 and 9, and the legs of the driven staple will be clinched in the grooves 7 of the anvil 6. During the application of the first staple S to the work the rearwardly-extending finger 39 on the reciprocating member 38 of the stitching head 2 will engage and actuate the arm 37, see Fig. 6, to turn the rock-shaft 36 on the gauge 18 from the position shown in Fig. 7 to that shown in Fig. 8. Upon such turning motion of the rock-shaft 36 the abutment 91 at the end of the arm 90 will engage and rock the trip-member 79 on its pivots 80 to the position shown in Fig. 8 to raise the extension 78 to a position above the upper edge of the abutment 46 against the tension of the spring 89. After the extension 78 has disengaged the abutment 46 the spring 28, see Fig. 6, will slide the plate 21 of the gauge 18 forwardly to its initial position indicated by dash-lines in Fig. 4 to release the push-buttons 26 and 27 of the electrical switches, at which time its forward end will overlie the upper edge of the abutment.

Simultaneously with the operation of the stitching head 2 the drive-shaft 4 will operate through suitable mechanism to rock the shaft 15 mounting the lower feed-rolls 9. Rocking motion of the shaft 15 will be transmitted through the crank-arm 55 and abutment 57 to rock the arm 54 upwardly whereby to move the lower auxiliary feed-roll 45 toward the upper feed-roll 44 to firmly grip the carton-blank therebetween.

After the first staple S has been applied to stitch the manufacturer's seam of the carton-blank W the upper auxiliary feed-roll 44 will be rotated from the shaft 10, operating through the intermeshing gears 52, 51 and 50, to advance the box-blank a predetermined distance between stitches. The continued movement of the box-blank W will cause the abutment 46 to be rocked to the position shown in Fig. 5 and the leading end of the blank will be advanced through the space between the abutment and the extension 78 of the trip-member 79 in the manner indicated in Fig. 5 until the leading edge of the blank is gripped between the main feed-rolls 8 and 9. The wire-stitching head 2 will continue to operate to apply staples S to the work as the main and auxiliary feed-rolls 8, 9 and 44, 45 rotate in timed

relation to the operation of the stitching means until the stitching of the manufacturer's seam is completed. During the stitching of the seam of a box-blank W of the type herein shown the depending flange 85 of the extension 78 on the trip-member 79 will ride on the top of the blank to provide a single line of contact of the gauge with the blank.

Upon completion of a stitching operation the shaft 10 will be connected to the continuously-operating driving means to discharge the stitched box from the machine and the shaft 15 will be rocked to return the lower feed-rolls 9 and 45 to their normal spaced relationship as illustrated in Fig. 1. As the rearward end of the stitched box releases the abutment 46 the spring 69 will rock it to the upright position shown in Fig. 3, the rocking movement of the abutment being limited by the engagement of its bottom edge with the top of the blocks 64 and 65 on the supporting plate 66. During the rocking movement of the abutment 46 to its upright position the inclined cam-face 86 at the forward end of the depending flange 85 of the extension 78 will be engaged by the upper edge of the abutment to rock the trip-member 79 on its pivots 80 to permit the abutment to pass by its end. The trip-member 79, however, will be rocked by the spring 89 to engage the forward end of its extension 78 with the rearward side of the abutment 46 as illustrated in Fig. 3. The machine is then ready for another stitching operation.

It will be understood that by adjusting the plate 66 along the table 5 the abutment 46 may be positioned in relation to the stitch-line of the wire-stitching head 2 so that the first stitch will be applied to the work at any desired distance from its forward edge. If it is desired to stitch the usual type of slotted carton-blank the auxiliary feed-rolls 44 and 45 may be removed readily from the machine and the usual depending abutment such as illustrated in my prior patent may be substituted for the abutment 46, supporting plate 66 and rockable trip-member 79. As stated above, the auxiliary feed-rolls 44 and 45 and the improved form of gauge 18 may be applied to the type of wire-stitching machine illustrated and described in my prior Patent No. 2,266,550 issued December 16, 1941. In this type of machine separate step-feed and discharge rolls are provided on opposite sides of a rockable cradle. When the auxiliary feed-rolls 44 and 45 are to be applied to this latter type of machine the arm 54 mounting the lower auxiliary feed-roll 45 will be mounted on the rock-shaft of the cradle and operated in the same manner as explained above.

It will be observed from the foregoing specification that the present invention provides improvements in wire-stitching machines to adapt them to stitch the manufacturer's seam of carton or box-blanks closely adjacent the leading edges thereof as they are fed forward in the machine. It will be observed also that the present invention provides a novel form of gauge adapted to be adjusted to a position closely adjacent the stitch-line of the wire-stitching means. It still further will be observed that the present invention provides for the application of the auxiliary feed-rolls and gauge as attachments to standard machines.

While a preferred form of construction of the improvement in wire-stitching machines is illustrated and described herein, it is to be understood that modifications may be made in the structure and arrangement of the mechanism thereof with-

out departing from the spirit or scope of the invention. Therefore, without limiting myself in this respect, I claim:

1. In a machine of the type indicated, wire-stitching means, work-feeding means, a work-operated gauge comprising means engageable by the work, and control-means actuated by the gauge for initiating operation of the wire-stitching means, said work-feeding means being positioned forwardly of the stitch-line of the wire-stitching means to adapt the work to be advanced as it is stitched closely adjacent its leading edge.
2. In a machine of the type indicated, wire-stitching means for stitching the manufacturer's seam of a box, work-feeding means for advancing the box-blank between stitches, a work-operated gauge having means engageable by the leading edge of the blank closely adjacent the stitch-line of the wire-stitching means, and control-means actuated by the gauge for initiating operation of the wire-stitching means, said work-feeding means being positioned forwardly of the stitch-line of the wire-stitching means to adapt the box-blank to be advanced thereby as it is stitched closely adjacent its leading edge.
3. In a machine of the type indicated, wire-stitching means for stitching the manufacturer's seam of a box, work-feeding means for advancing the box-blank between stitches, a work-operated gauge having means engageable by the leading edge of the blank, means permitting adjustment of the gauge relative to the stitching means to a position closely adjacent the stitch-line thereof, and control-means actuated by the gauge for initiating the operation of the wire-stitching means, said work-feeding means being positioned forwardly of the stitch-line of the wire-stitching means to adapt the box-blank to be advanced thereby as it is stitched closely adjacent its leading edge.
4. In a machine of the type indicated, wire-stitching means for stitching the manufacturer's seam of a box, work-feeding means for advancing the box-blank between stitches, a work-operated gauge having means engageable by the leading edge of the blank closely adjacent the stitch-line of the wire-stitching means, control means actuated by the gauge for initiating operation of the wire-stitching means, auxiliary work-feeding means positioned forwardly of the stitch-line of the wire-stitching means to advance the blank to the first-mentioned feeding means to provide for stitching it closely adjacent its leading edge, and means for driving the auxiliary feeding means in synchronism with the wire-stitching means.
5. In a machine of the type indicated, wire-stitching means for stitching the manufacturer's seam of a box, feed-rolls at the rear of the wire-stitching means for advancing the box-blank between stitches, a work-operated gauge having means engageable by the leading edge of the blank closely adjacent the stitch-line of the wire-stitching means, control-means actuated by the gauge for initiating operation of the wire-stitching means, auxiliary feed-rolls positioned forwardly of the wire-stitching means, and means for driving the auxiliary feed-rolls from the first-mentioned feed-rolls whereby to adapt them to feed the blank as it is stitched closely adjacent its leading edge.
6. In a machine of the type indicated, wire-stitching means for stitching the manufacturer's seam of a box, cooperating upper and lower feed-rolls at the rear of the wire-stitching means,
- 5
- means for relatively moving the feed-rolls toward each other to grip the box-blank therebetween and advance it between stitches, a work-operated gauge comprising means engageable by the leading edge of the blank closely adjacent the stitch-line of the wire-stitching means, control-means actuated by the gauge for initiating operation of the wire-stitching means, cooperating upper and lower auxiliary feed-rolls positioned forwardly of the stitch-line of the wire-stitching means, means for driving the auxiliary feed-rolls in synchronism with the first-mentioned feed-rolls, and means for relatively moving the auxiliary feed-rolls toward each other to grip the box-blank therebetween as it is stitched closely adjacent its leading edge.
7. In a machine of the type indicated, wire-stitching means for stitching the manufacturer's seam of a box, cooperating upper and lower feed-rolls at the rear of the wire-stitching means, means for moving the lower feed-rolls toward the upper feed-rolls to grip the box-blank therebetween and advance it between stitches, a work-operated gauge comprising means engageable by the leading edge of the box closely adjacent the stitch-line of the wire-stitching means, control-means actuated by the gauge for initiating operation of the wire-stitching means, cooperating upper and lower auxiliary feed-rolls positioned forwardly of the wire-stitching means, means for driving the upper auxiliary feed-roll from the first-mentioned upper feed-roll, and means for moving the lower auxiliary feed-roll toward the upper auxiliary feed-roll to grip the box-blank therebetween as it is stitched closely adjacent its leading edge.
8. In a machine of the type indicated, wire-stitching means, work-feeding means, an abutment pivotally mounted to adapt it to be rocked by the work, means operated by the rocking movement of the abutment for initiating operation of the wire-stitching means, means for connecting the abutment to the means operated thereby, and means actuated by the wire-stitching means for releasing said connecting means to disconnect the abutment from the means operated thereby to permit the work to pass therebetween.
9. In a machine of the type indicated, wire-stitching means, work-feeding means, a work-supporting table, an abutment pivotally mounted on the table to adapt it to be rocked by the work, means operated by the rocking movement of the abutment for initiating operation of the wire-stitching means, means for connecting the abutment to the means operated thereby, and means actuated by the wire-stitching means for releasing said connecting means to disconnect the abutment from the means operated thereby to permit the work to pass therebetween.
10. In a machine of the type indicated, wire-stitching means, work-feeding means, an abutment mounted for pivotal movement to adapt it to be rocked by the work, a gauge comprising a slide, a trip-member on the slide engageable by the abutment for actuating the slide, means actuated by the slide for initiating operation of the wire-stitching means, and means operated by the wire-stitching means for actuating the trip-member to release the abutment whereby to permit the work to pass therebetween.
11. In a machine of the type indicated, wire-stitching means for stitching the manufacturer's seam of a box, work-feeding means for advancing the box-blank between stitches, a work-sup-

porting table below the wire-stitching means, an abutment pivotally mounted on the table and adapted to be engaged and rocked by the work, a slide supported by the wire-stitching means in spaced relation to the table, a trip-member on the slide engageable by the abutment for actuating the slide, means actuated by the slide for initiating operation of the wire-stitching means, and means operated by the wire-stitching means for actuating the trip-member to release the abutment whereby to permit the work to pass therebetween.

12. In a machine of the type indicated, wire-stitching means for stitching the manufacturer's seam of a box, means for advancing the box-blank between stitches, a work-supporting table below the wire-stitching means, an abutment pivotally mounted on the table and adapted to be engaged and rocked by the blank, means operated by the abutment for initiating operation of the wire-stitching means, means actuated by the wire-stitching means to release the abutment from engagement with the means operated thereby to permit the work to pass therebetween, and means for mounting the abutment and the means operated thereby to permit adjustment thereof to a position closely adjacent the stitch-line of the wire-stitching means.

13. In a machine of the type indicated, wire-stitching means, work-feeding means, an abutment mounted for pivotal movement and adapted to be engaged and rocked by the work, a slide, a trip-member pivotally mounted on the slide, said trip-member normally being positioned for

engagement and actuation by the abutment, means operable by the slide to initiate operation of the wire-stitching means, a rock-shaft, an arm on the rock-shaft for engaging the trip-member to release it from engagement with the abutment, and means operated by the wire-stitching means to rock the rock-shaft.

14. In a machine of the type indicated, wire-stitching means, work-feeding means positioned forwardly of the stitch-line of the wire-stitching means, an abutment pivotally mounted for rocking movement by the work, means operated by the rocking movement of the abutment for initiating operation of the wire-stitching means, and means operated by the wire-stitching means to disconnect the abutment and the means operated thereby to permit the work to pass therebetween.

15. In a machine of the type indicated, wire-stitching means for stitching the manufacturer's seam of a box, work-feeding means positioned forwardly of the stitch-line of the wire-stitching means for advancing the work between stitches, a work-supporting table below the wire-stitching means, an abutment pivotally mounted on the table closely adjacent the stitch-line of the wire-stitching means to adapt it to be rocked by the work, means operated by the rocking movement of the abutment for initiating the operation of the wire-stitching means, and means operated by the wire-stitching means to disconnect the abutment and the means operated thereby to permit the work to pass therebetween.

GEORGE H. HARRED.
